United States Patent Office

Des. 183,477
Patented Sept. 9, 1958

183,477

CHRISTMAS ORNAMENT OR SIMILAR ARTICLE

Jack Burnbaum, Newton, Mass., assignor to Bradford Novelty Co., Inc., Cambridge, Mass., a corporation

Application March 25, 1957, Serial No. 45,408

Term of patent 14 years

(Cl. D29—1)

Fig. 1.

Fig. 2.

Fig. 3.

Fig. 4.

Fig. 1 is a top plan view of a Christmas ornament embodying my new design.

Fig. 2 is a bottom plan view thereof,

Fig. 3 is a side elevational view thereof, and

Fig. 4 is a different side elevational view thereof.

I claim:

The ornamental design for a Christmas ornament or similar article, substantially as shown.
